RECTANGULAR BELL-TYPE FURNACE HOOD

Frederick R. J. Davis, Irwin, Pa., assignor to
Westinghouse Electric & Manufacturing Com-
pany, East Pittsburgh, Pa., a corporation of
Pennsylvania

Application August 7, 1937, Serial No. 157,853

10 Claims. (Cl. 263—49)

My invention relates to annealing furnaces and the like and particularly to rectangular bell-type furnace hoods therefor.

In some rectangular hoods for such furnaces known to the art, partially fluted sides and top portions have been employed. However, this structure could not be used with a skirt as it will not permit the proper expansion and contraction between the hoods proper and the skirt. Moreover, the fluted portions of the sides and tops have extended to within a few inches from the junction between the top plate and the sides. The inability to extend the flutes in a continuous path up one side, across the top and down the other side has further limited the field of application of the rectangular hoods because, by not having the flutes in such a continuous path, the hoods cannot freely expand and contract.

Different manners of forming the sides and top of the hood are well known to the art. For example, a single sheet of metal may be made to extend vertically as one side of the hood, be bent or otherwise formed to extend horizontally to form the top of the hood, and then bent or otherwise turned downward to form the opposite side of the hood. In another construction a sheet forms one side only of the hood, the upper edge being welded to the edge of the top contiguous thereto. Whatever construction is employed, it is usual to provide transverse corrugations or flutes in the sheets to permit expansion and contraction of the hood, as well as to strengthen it.

In a construction where a weld is present between a side wall and the top wall I have tried placing right angle flute inserts directly between the top and side flutes in which the weld between such flutes and inserts joined at the junction of the top plate and side walls. While this structure will satisfactorily operate for a certain length of time, since it necessarily involves the concentration of three perpendicular welds at substantially a point subjected to frequent bending, sooner or later the expansion and contraction of the hood will weaken the weld at this point of concentrated stress, and the structure will crack open, thus permitting escape of the treating atmosphere and spoilage of the charge.

It is, therefore, an object of my invention to provide a fluted rectangular bell-type hood with flutes which extend in a continuous path, up one side, across the top and down the other side, which will permit the hood to safely expand and contract with large differences in temperature without causing undue distortion of the hood or overstressing of the weld joints.

A further object of my invention is to provide a fluted hood having a skirt which will be capable of expansion and contraction with respect to the outer edge of the skirt without causing undue distortion of the hood.

Another object of my invention is to provide a fluted hood which will not have any welded junction located within the flutes or in the flutes at the bend between the top and the side and which will be sufficiently strong and safe enough to guard against the loss of gas located therein.

Other objects of my invention will either be pointed out specifically in the course of the following description of a device embodying my invention, or will be apparent from such description.

In the accompanying sheets of drawings:

Figure 1 is a transverse sectional view of a device such as an annealing furnace embodying my invention;

Fig. 2 is a view similar to Fig. 1 showing a modified form of my invention;

Figs. 3 and 4 are a top view and a side elevational view, respectively, of the hood shown in Fig. 1;

Fig. 5 is a sectional view taken along line V—V of Fig. 3;

Figs. 6 and 7 are sectional views taken along lines corresponding to line VII—VII of Fig. 3 showing partial sectional views of modified corners of the hoods shown in Figs. 1 and 2;

Fig. 8 is a sectional view taken along line VIII—VIII of Fig. 3;

Figs. 9 and 10 are detail views of the fluted insert bend shown in Fig. 5, and

Fig. 11 is a perspective view of a flute, showing in particular a bend thereof of the type illustrated in Fig. 5.

Referring to Figures 1, 3 and 4, I show a rectangular bell-type furnace 10 including a furnace bell 12 and a base 14, a rectangular fluted hood 16 (or 18 Fig. 2) being located within the bell 12.

The rectangular furnace bell 12 may be composed of fire clay brick 20 or of any other suitable material which will not break down under the heat, substantially 1500 to 1700° F., to which it will be subjected. The heat may be supplied to the furnace by means of suitable electric heating elements 22, for example, located on the inner walls of the bell in any suitable manner. However, it is to be understood that heat may be supplied to the furnace in any other desired manner. A suitable supporting plate 24 may be located in the bottom portion of the furnace bell 12 to rigidly support the fire clay brick 20. A

suitable bar 26 may be rigidly attached below and near each side of the plate 24 to support the furnace bell 12 upon the outer part of a skirt 27 preferably integral with fluted hood 16, as hereinafter described, and at a suitable distance above the base 14, so that the weight of such furnace bell will not be carried upon the inner or fluted part of skirt 27, and to permit such weighted skirt to function as a preliminary gas seal. The furnace bell 12 may be removed from or replaced on the base 14 by means of a hook (not shown), or by any other suitable means.

The furnace base 14 may be constructed in any suitable manner. However, it is preferred that such base be composed of fire clay brick having such compression strength that it will adequately support the furnace bell 12, the hood 16 and any desired charge located within the hood. An upwardly protruding hearth 28 may be located substantially in the center of the furnace base 14 and may have a hearth plate 30 located thereon for supporting any desired charge. A trough 32 may be located along the outer edge of the base 14 for holding any suitable sealing medium 34, such as oil, which may be operatively associated with the hood 16 by means of the skirt 27, as hereinafter described.

The rectangular fluted bell-type hood 16 comprises upstanding side walls 40 and a top plate 42. The side walls 40 have located, preferably integrally, therein, a plurality of flutes 44 extending from substantially the bottom edge to the top edge thereof. Likewise, the top plate 42 has a plurality of preferably integral flutes 46 extending transversely across such plate to register and cooperate with the vertically upstanding flutes 44. In addition, the hood 16 of Fig. 1 includes the skirt 27 extending substantially at right angles to the side walls 40, and which has located thereon flutes 50 which register and cooperate with the flutes 44 located within the side walls 40.

The top plate 42 may be formed as a separate integral piece free from the side walls 40 and may be rigidly attached thereto by welding its edges to the top edges of the side walls, although a portion of the top plate 42 may be integral with one side wall.

However, it is preferred that the hood side walls 40 and top plate 42 be shaped from a continuous sheet of material extending upwardly from substantially the bottom edge of one of the side walls to form such side wall, across the top to form the top plate, and downwardly to form the opposite side wall. The flutes 44 and 46 may also be formed in the continuous sheet to provide the necessary expansion joints and stiffening. Such flutes will then be in a continuous path, without having any welds therein, progressing up one side wall across the top and down the opposite side wall. The shape of the flutes at the change from a vertical flute 44 to the horizontal flute 46 occurs will then be substantially as shown in Fig. 7.

By using the preferred constructions of Figs. 1 and 2, which, as hereinabove described, has the side walls 40 and top plate 42 formed from a continuous sheet of material with the flutes 44 and 46 formed therein, there will be no welds in the flutes located at the junction between the top plate and the side walls. This will permit the top portion of the hood to expand and contract transversely as well as longitudinally without any danger of warping the hood or of a fracture between the side walls 40 and top plate 42 themselves or between the flutes 44 and 46, thereby

ensuring a permanent, flexible, impervious enclosure for the gas located within it.

When the construction of the hood is such that one or both side walls are formed independently of the top wall, a weld joint is usually employed to unite the parts into a unitary structure. With such construction, the flute 46 in the top wall is made functionally continuous, in my construction, with the side flute 44 by means of an irregularly-shaped flute insert 52, preferably of the form shown in Figs. 9 and 10, welded in position as shown in Figs. 5 and 11.

The insert 52 is diamond shaped and corrugated to form a diagonal flute with two upstanding ends 53 preferably having acute angles somewhat less than a right angle. The side 40 and top 42 (Fig. 11) are properly cut out to mate with the insert. When welded in position, the junction of the corner of the ends 53 and the bend between the side and top wall is spaced from the flute portion of the insert so that this junction is not subjected to bending stresses or to forces at right angles which would be the case if a customary right angular corner insert were employed. The stresses at the junctions 53' are now between the insert and top or between the insert and side wall, and at no point of the flute of the insert do the stresses, created by changes in the top, side wall, and flute, act simultaneously.

It may be observed, then, that the insert 52 is welded to the vertically upstanding flutes 44 and to the horizontal flutes 46, at some distance from the junction of side wall 40 and top plate 42, thereby forming a continuous flute progressing up on one side wall, across the top plate and down the other side wall.

By having the irregularly shaped flute insert 52 located between the top flutes 46 and the side flutes 44, it is obvious that there will be no weld or junctions on the flutes in line with the integral or welded junction of the top and side walls.

It is to be understood that the irregular shaped flute insert 52, shown in Figs. 5, 9, 10 and 11 may be used to obtain the bend between the top flutes 46 and side flutes 44, regardless of whether the top-plate 42 and side walls 40 are formed from individual sheets or from a single sheet. However, when the insert 52 is used with the single sheet hood it is obvious that it is not necessary to form flute corner bends in such sheet, it merely being necessary to form the top and side flutes and leave an opening in such sheet for the flute insert. With this structure also, it is apparent that there will be no welds located within the flute in line with junction of the top and side walls.

As an additional modification, the top plate 42 may be somewhat smaller than the distance between the side walls 40 and disposed somewhat above the edge of the side walls, the plane between the edges of the walls preferably forming a 45° angle as shown more particularly in Fig. 6, and an additional fluted plate 54, with the flutes 56 thereof trapezoidal in side elevation, may be located at substantially a 45° angle between said top plate and the side walls, as shown in Fig. 6. The additional plate 54 is of an extended length, and after being fluted, may be welded to the sides 40 and top plate 42 with the flutes 56 located therein welded to the side flutes 44 and top flutes, respectively, to form continuous gas-tight flutes which progress up one side wall, across the top and down the second side wall. By using the additional fluted plate having flutes therein, be-

tween the top-plate 42 and the side walls 48 it is obvious that there cannot be a common welded junction between the flutes, side walls and top wall.

5 If it be desired, flutes 44a shown in Figs. 3 and 4, may be located within the end walls of the hoods to permit the hood to expand and contract without warping the structure. However, when using such flutes, the top plate 42 will have to 10 have a tongue integral therewith to seal the open end of the flute 44a or a small insert plate should be used to block off the top opening of such flute to make it gas-tight.

The skirt 27 located at the bottom portion of 15 the hood 16 is rigidly attached to the side and end walls 40 of such hood, preferably by welding. A depending portion 58 is located at the outside ends of the skirt 27 to project downwardly into the sealing trough 32 and into the 20 sealing medium 34, preferably oil, to produce a gas-tight seal for the hood. The skirt 27 is of such a length, with respect to the furnace bell 12 and fluted hood 16, that it extends outside the furnace bell 12. Because the outside end and 25 depending portion 58 of the skirt 27 extend outside the furnace, the temperatures of such portions of the skirt 27 will be considerably below the temperature within the furnace bell. The inside temperature may be 1500 to 1700° F., while 30 the outside temperature is substantially 150° F.

Due to the extreme differences in temperature between the inside and the outside of the fluted hood 16 it is necessary to provide additional means for permitting the inside portion of the 35 skirt 27 to expand and contract with respect to the outside portions thereof. To permit this expansion and contraction, without undue warping of the hood 16, including skirt 27, it is necessary to slot the inside portion of the skirt 27 substantially normal to the plane of the side walls. 40 These slots 60, shown in Figs. 6, 7 and 8 are covered by the flutes 58 which also extend substantially at right angles to the side walls of the hood 16. The flutes 58 are rigidly attached to the skirt, 45 preferably by welding. The slots 60 in cooperation with the flutes 58 permit the inside portion of the skirt 27 to expand and contract transversely to the slots 60, with respect to the outside portion of the skirt 27, without causing the skirt to warp. The cooperation of flute 58 with skirt 50 27, inasmuch as they are rigidly attached thereto and form a gas-tight seal therewith, prevents the controlled atmosphere located within the hood from leaking out via the slots 60.

55 The flutes 58 and end wall flutes 58a located over the slots 60 cooperate with and are rigidly attached to the flutes 44 and 44a, respectively, in such a manner that their junction will be gas-tight. By having the flutes 58 cooperate with the 60 flutes 44, it is obvious that flutes will be provided which extend continuously along the skirt, up one side, across the top, down the other side and along the opposite side of the skirt.

By having the flutes 58 extending out over slots 65 60 located within the skirt 27, and by having continuous cooperative flutes progressing transversely of the walls of hood 16, such hood 16, including the inner portion of skirt 27, may expand and contract freely without serious distortion with respect to the outer edge of the skirt.

If it be preferred, a plurality of troughs 58 may be located a short distance from the hearth 28 as shown in Fig. 2 in which a suitable sand seal 61 may be located, and such sand seal 61 may be used with bell-type hood 16 which does not have

a skirt. It being understood that hood 16, which cooperates with a sand seal located within the furnace, is otherwise similar to hood 16, which cooperates with the oil seal located outside the furnace, except hood 16 does not have a skirt associated therewith.

The top plate and the top portion of the side walls of the hoods 16 and 18, when expanding, bow upwardly and outwardly with respect to the bottom portion of the hoods, causing the top plate to arch slightly and the side walls to be slightly angularly displaced. This expansion and arched relative movement between the top portion, including the top plate and side walls, and the bottom portion of the hood cause serious 10 stresses and strains at the bends in the flutes. With repeated operations of the hood, any welds located at the bends in the flutes subjected to stress from both the top and side walls will crack, thereby making the hood inoperative, as the gas 15 located therein will readily escape therefrom.

However, by having continuous flutes with no welds therein in line with the integral or welded junction of the top and side walls, as hereinabove described, or employing a flute insert such as 52, 25 20 or a corner plate 54 properly fluted, the tendency for cracks to develop at the bends is substantially eliminated. This reduction in the possibility of cracks developing is especially true where the flutes 44 and 46, side walls 48 and top plate 30 35 42 are shaped from one continuous sheet, as shown in Fig. 7, as there are no longitudinal welds necessary at the bends of the flutes, and, therefore, the internal stresses and strains cannot be concentrated at one point at such bend.

It is to be understood that there may be longitudinal welds within the hoods 16 and 18 at points other than the bends within the flutes, such as along lines 62 or 64 as shown in Fig. 7, without increasing the stresses at the flute bends or causing 40 such bends to fracture.

It is, therefore, obvious that by using the preferred form of structure as hereinabove described, in which the side walls, top plate and the flutes located therein are formed from one continuous 45 sheet without having any welds located within the flutes, such structure will not rupture at the bend between the top flutes and the side flutes.

It is to be understood, however, that if the over-all length of the fluted hood is greater than 50 the width of commercial sheets and it be desired to have the flutes run parallel to the longitudinal axis of the sheets, such hood may be formed of two or more sheets welded together parallel with the hood's transverse axis, as shown by line 66 55 55 in Figs. 3 and 4, so that the flutes will be entirely within one sheet and extend parallel to the transverse axis of such hood. The hood may also be formed so that at least a portion of the top plate is integral with one side wall, or with at least two 60 sheets extending substantially parallel to the transverse axis of the hood. These two sheets should be joined so that their junction would not be at a bend between the top and side walls, as shown by line 62 in Fig. 3. It therefore follows that if the hood be formed of a plurality of sheets, the junctions therebetween may extend parallel with a transverse line through the hood and may be located at points remote from the flute bends, 70 as shown by lines 66 and 62 respectively, in Figs. 3 and 4.

It is, therefore, obvious that hoods as hereinabove described, may be used within a bell type furnace and operated through repeated cycles 75

without any danger of the hood fracturing at the junction or bend between the top flutes and the side flutes, and that due to such fluted structure of the hood, such hood may expand and contract in relation to the outer edge of the skirt located integrally therewith.

I desire it to be understood that the term "continuous flute" in the appended claims, is employed to cover any of the types of flutes shown on the drawings which, whether integrally or otherwise formed, provide uninterrupted or gas-tight flutes or channels.

Various further modifications may be made in the device embodying my invention without departing from the spirit and scope thereof, and I desire, therefore, that only such limitations shall be placed thereon as are imposed by the prior art and the appended claims.

I claim as my invention:

20. 1. In a rectangular bell type furnace, a rectangular hood including substantially vertical side walls, a top plate and a skirt, a plurality of continuous flutes running along at least a portion of said skirt, up one side, across the top, and down the other side of the hood, and means comprising said flutes for permitting the expansion and contraction of said hood.
25. 2. In a rectangular bell type furnace, a rectangular hood including substantially vertical side walls, a top plate and a skirt, a continuous sheet of material extending upwardly to form one of said side walls, across the top to form the top plate and downwardly to form the other of said side walls, a plurality of continuous flutes running along at least a portion of said skirt, up one side, across the top, and down the other side of said hood, and means comprising said flutes for permitting the expansion and contraction of said hood.
30. 3. In a rectangular bell-type furnace, a rectangular hood including substantially vertical side walls, a top plate, and a skirt, said side walls, skirt and top plate comprising a plurality of sheets rigidly attached together, a plurality of continuous flutes, each entirely formed in one sheet, their ends registering so that the flutes as a whole run along at least a portion of said skirt, up one side, across the top and down the other side, and means comprising said flutes for permitting the expansion and contraction of said hood with respect to the skirt.
35. 4. In a rectangular bell type furnace, a rectangular hood including substantially vertical side walls and a top plate and a slotted skirt, a continuous sheet of material extending upwardly to form one of said side walls, across the top to form the top plate and downwardly to form the other of said side walls, a plurality of continuous flutes running along at least a portion of said skirt and over said slots, up one side, across the top and down the other side of said hood, and means comprising said slotted skirt and flutes for permitting the expansion and contraction of said hood with respect to the skirt.

5. In a rectangular bell-type furnace, a rectangular hood comprising joined top and side walls, aligned flutes therein terminating short of the junction of the corresponding walls, a four-sided insert with a diagonally-extending, central flute therein having two opposite non-fluted corners disposed in alignment with said junction and being secured to the adjacent walls along parts of its edges extending away from said corners, the flute in said insert being secured at its respective ends to the adjacent flutes in said walls.

6. In a rectangular bell-type furnace, a rectangular hood comprising joined top and side walls, aligned flutes therein terminating short of the junction of the corresponding walls, the terminating planes of said flutes converging inwardly, and an insert having a flute therein, the ends of said insert flute being secured to said converging ends of said wall flutes to form a continuous gas-tight passage.

7. In a furnace, a rectangular hood comprising continuous substantially vertical side walls and an intermediate top wall, said walls including at least one continuous, transverse flute, said flute comprised of a substantially centrally fluted insert disposed at the junction of said top wall and one of said side walls, said insert being so shaped and welded to said walls that the weld points at the common junctions of the insert, said top wall, and said one side wall are removed from said flute.

8. In a furnace, a rectangular hood comprising joined top and side walls, transverse aligned flutes in said walls, and a fluted insert forming a connecting bend for said flutes whereby to render the same functionally-continuous, said insert being shaped to be secured to said hood at the junction of said top and side walls along lines extending from the flute and angularly related to the junction of said walls, said insert being secured to said walls in a substantially gas-tight manner.

9. In a furnace of the type having therein a substantially gas-tight hood for enveloping a charge resting on a base, a hood comprising a side wall having upstanding flutes therein, a horizontal skirt secured to the bottom of said wall, said skirt having slots extending from the secured edge for some distance toward the other edge, and flute structures secured to said skirt and said flutes and above said slots in a gas-tight manner.

10. In a furnace of the type having therein a substantially gas-tight hood for enclosing a charge space, said hood comprising a side wall and top wall having transverse flutes, said walls having edges terminating short of each other and at an angle to both of substantially 45 degrees, and a fluted plate secured in a gas-tight manner to said edges whereby to seal the walls, the flutes of said plates being aligned with the flutes in said walls.

FREDERICK R. J. DAVIS.

CERTIFICATE OF CORRECTION.

Patent No. 2,175,829.

October 10, 1939.

FREDERICK R. J. DAVIS.

It is hereby certified that error appears in the printed specification of the above numbered patent requiring correction as follows: Page 3, first column, line 9, for "platt" read --plate--; page 4, first column, line 23, claim 1, for "flues" read --flutes--; and that the said Letters Patent should be read with this correction therein that the same may conform to the record of the case in the Patent Office.

Signed and sealed this 27th day of July, A. D. 1943.

(Seal)

Henry Van Arsdale,
Acting Commissioner of Patents.
